UNITED STATES PATENT OFFICE.

ALTON E. COBB AND HARRY L. PARKER, OF LOS ANGELES, CALIFORNIA.

SUCTION-POUNDER FOR WASHING-MACHINES.

1,072,342.

Specification of Letters Patent.

Patented Sept. 2, 1913.

Application filed June 2, 1911, Serial No. 630,807. Renewed April 14, 1913. Serial No. 761,048.

To all whom it may concern:

Be it known that we, ALTON E. COBB and HARRY L. PARKER, citizens of the United States, residing at Los Angeles, in the county of Los Angeles and State of California, have invented certain new and useful Improvements in Suction-Pounders for Washing-Machines, of which the following is a specification.

10 This invention relates to suction pounders for washing machines, and belongs particularly to that class of washing machine devices that are arranged over suitable tubs or tanks, and are provided with mechanism for working them up and down. The upward movement creates a partial vacuum and the wet fabric within the tub is temporarily held to the pounder cylinder by atmospheric pressure, and is released by the downward movement, the fabric and the fluid being by such movements correspondingly agitated.

15 The object of this invention is the production of a suction pounder comprising parts of special construction and arrangement with relation to each other, whereby it is believed the soiled articles of clothing or the like, are rapidly raised and lowered with very little danger of being torn, and the power necessary to operate the pounder cylinder is much reduced by reason of the fact that the partial vacuum is effectively created very quickly, and is as quickly and thoroughly broken. It is thought that if the 20 partial vacuum is quickly broken and the fabric at once released, the probability is increased that it will be taken in a different place by the next upward movement. That is to say, a different portion of the fabric will be held to the pounder cylinder as it is raised, and all portions thereof opened and exposed to the cleansing fluid.

25 The construction and arrangement of parts comprising this invention, with the preferred means for operating the same are illustrated in the accompanying drawings, of which—

30 Figure 1 represents an elevation partly in vertical section showing all the parts in their relative positions. Fig. 2 is a view from below, with a portion of the perforated bottom broken away to disclose internal parts.

35 Throughout the drawings and description, the same letter is employed to refer to the same part.

The standard A, at its upper end, supports by means of the pivot pin *a*, the rocker arm B, that is attached to and operated by the upwardly-projecting handle *b*. Pins *c* 50 and *c* project from the ends of the rocker arm, and engage the tapering orifices *D* and *d* in the piston rods *E* and *e*, of the two pounder cylinders *F* and *f*.

As the construction of both washers or 55 pounder cylinders *F* and *f* is the same, the following description of one will apply to both. The piston rod *E* of pounder cylinder *F*, passes downwardly through the tubular casing *G*, and a coil spring *g* encircles the 60 rod *E* within the casing *G*. One end of the spring is attached to the rod and the other end to the inside of the casing, so that when the rod is depressed the spring is compressed, and, the rod is raised by the reaction of the spring.

65 The casing *G* is joined to the conical casing *H*, and, attention is here called to the fact that the lower edge *h* of the conical casing projects downwardly beyond the 70 pounder cylinder *F*, to which the conical casing is joined, and over a circular series of holes *J* through the pounder cylinder near the top thereof. These parts will be again referred to. The bottom of the cylinder is 75 closed by the perforated plate *K*. Within the pounder cylinder *F*, and arranged to operate up and down above the perforated plate *K*, is the plunger or piston *k*, joined to the piston rod *E* by the braces *L*. Immediately above the piston and normally resting upon it, is the valve plate *M*, through 80 which the piston rod *E* passes movably, and the rod is connected with the center of the piston *k*. It will be understood, therefore, 85 that the piston rod *E* is attached to the piston *k* at its middle point, and, also, rod *E* is connected with the piston *k* by braces *L* as set forth. The valve plate *M* normally 90 closes the openings *m* in the piston *k*. There 95 may be any desired number of such openings.

90 In the operation of this invention, the piston rod *E* is forced downwardly by rocking the arm *B* by means of handle *b*. In Fig. 1, 105 it will be observed, that as the handle *b* is moved into its vertical position one of the pistons creates suction as it rises. Let it be assumed that the pounder cylinders were 110 placed in a tub containing water and clothes to be washed. The suction holds a portion of the clothes to the perforated bottom of

the pounder cylinder while the handle is brought into its vertical position. Now, the operator having by suction a suitable hold upon the clothes and the handle vertical, moves the pounders and the clinging clothes up and down in the water, materially aiding the cleansing operation. Now, when the piston *h* is raised, it sucks the water through that portion of the clothes held by suction 5 against the perforated plate *K*, and, when the piston moves down again, the dirty water just mentioned as drawn through the clothes, passes upwardly through the holes *m* in the piston, and is prevented from returning by the valve plate *M*. As the piston again rises, the dirty water is expelled through the circular orifices *J* near the top 10 of cylinder *F*. That is to say, the dirty water sucked through the clothes is not returned directly to the clothes again, but, is discharged into the whole body of water in the tub or tank, and mixed with clean water. It will be noted in Fig. 1 that the series of 15 orifices *J* are beneath the overhanging edge *h* of the conical portion *H* of the casing, and, those orifices are in that manner guarded against the splashing back of the water through them, as the pounder cylinders are agitated. After the piston rod *E* has been 20 depressed, it is allowed to rise quickly under the force of the spring *g*, and a partial vacuum is formed within the cylinder, by the agency of which the clothes are held to the perforated bottom plate *K*, in the usual 25 manner, and the water sucked through the clothes. As soon as the piston starts down, the valve plate *M* lifts and instantly breaks the vacuum, and releases the clothes, which are moved more or less by the general disturbance, so that the device tends to operate 30 upon a new portion of the clothes at each stroke.

Having now described this invention and explained the mode of its operation, what we claim is:—

1. In a suction pounder for washing machines, the combination with a plurality of casings closed at the bottom, the bottoms of the casings being perforated, of means constructed and arranged to connect the casings rigidly together, pistons provided with valves and arranged in the casings and having rods extending upwardly through the tops of the casings, and a handle extending upwardly and pivotally connected with the said rods and with the said casing-connecting means whereby said handle may be vibrated back and forth through its vertical position to operate said pistons. 45

2. In a suction pounder for washing machines, the combination with a plurality of casings having conical tops and flat bottoms, said casings having circular series of holes near the top and the tops of the casings projecting downwardly and outwardly over said holes, the bottoms of the casings being perforated, of means constructed and arranged to connect the casings rigidly together, pistons provided with valves and arranged in the casings, said pistons having rods passing upwardly through the tops of the casings, and a handle extending upwardly and pivotally connected with the said rods and with the said casing-connecting means whereby said handle may be 60 vibrated back and forth through its vertical position to operate the pistons. 65

In testimony whereof we affix our signatures in presence of two witnesses:

ALTON E. COBB.

HARRY L. PARKER.
